RAILWAY SIGNALING

George R. Pflasterer, Swissvale, Pa., assignor to
The Union Switch & Signal Company, Swiss-
vale, Pa., a corporation of Pennsylvania

Application March 26, 1936, Serial No. 70,925

12 Claims. (Cl. 246—50)

My invention relates to railway signaling, and particularly to signaling involving wayside signals located along a trackway for governing the passage of trains.

5 The signaling system provided by this invention is similar to the system shown in application Serial No. 26,784 of James J. Vanhorn, filed June 15, 1935, and the system shown in application Serial No. 66,002 of Henry S. Young, filed February 27, 1926.

10 A feature of my invention is the provision of novel and improved apparatus for establishing a distinctive control for each of three track sections in the rear of an occupied section. Each distinctive control is effective to cause a corresponding aspect of the associated wayside signal, whereby there is produced a three-block, four-indication, system of signaling.

15 I will describe one form of apparatus embodying my invention, and will then point out the novel features thereof in claims.

20 In the accompanying drawings, Figs. 1A and 1B are diagrammatic views which, when placed end to end in the order named, illustrate one form of three-block, four-indication, signaling system embodying my invention.

25 Similar reference characters refer to similar parts in each of the views.

30 Referring to the drawings, the reference characters 8 and 9 designate the rails of a stretch of railway track along which traffic normally moves in the direction indicated by the arrows. The rails 8 and 9 are divided by insulated joints 14 into track sections W—X, X—Y, and Y—Z. As here shown, each track section is divided into two subsections 1T, 2T, 3T, 4T, etc.

35 Each subsection is provided with a track battery 15 connected across the rails at one end of the subsection and with a track relay, designated 40 by the reference character TR with a prefix the same as the numerical prefix of the associated subsection, connected across the rails at the other end of the subsection.

45 For governing the passage of trains along the stretch, each track section is provided with a wayside signal designated by a suitable distinguishing reference character. These signals may take any one of several forms of signal mechanisms such as searchlight, color light, position 50 light, or semaphore. As here shown, each signal is of the semaphore type and includes an upper indication unit U and a lower indication unit L. Each unit U is capable of assuming a horizontal or "stop" position, a 45° or "caution" position, 55 and a vertical or "proceed" position, and each

unit L is capable of assuming a horizontal or a vertical position but not a 45° position.

For controlling the signals, each section is provided with a direct current neutral home relay and with a direct current neutral distant relay 5 designated by the reference characters H and D, respectively, each with a prefix the same as the reference character of the associated signal. Also for controlling the signals, each section is provided with an alternating current auxiliary 10 relay designated by the reference character J with a prefix the same as the reference character of the associated signal.

Each section is provided with three line wires each extending through the section and each 15 including a front contact of each of the associated track relays. The associated relay H is directly connected with two of these line wires and the associated relay D is connected with the third wire and with one wire of the pair connected to the associated relay H. The associated relay J is connected to the same two wires as the relay D through a transformer and a condenser designated by the reference characters M and F, respectively, each with a prefix the same as the reference character of the associated signal. 20

The relatively high impedance of the relays H and D will prevent the flow of alternating current in these relays and the transformers and condensers will prevent the flow of direct current in the alternating current relays J. 25

Each section is provided with a suitable source of direct current here shown as a battery 16 with its terminals designated by the reference characters B and C.

35 Each section is also provided with a transformer designated by the reference character N with a prefix the same as the reference character of the associated signal and having a primary winding 17 and a secondary winding 18. The secondary winding 18 of each transformer N is connected in series with the third line wire for the section next in rear so that when alternating current is supplied to the primary winding 17, alternating current will flow over the line circuit 40 for the control of the relay J for the section next in rear. 45

For supplying alternating current to the primary winding 17 of the transformers N, each section is provided with a device, designated by 50 the reference character A with a prefix the same as the reference character of the associated signal, for converting direct current into alternating current. As here shown, each device A is an alternator of the well-known tuned reed type. 55

Referring to alternator 10A, for example, the reference character 21 designates a reed which is caused to vibrate between terminals 22 and 23 by a control winding 24. In the deenergized condition, reed 21 does not connect with either terminal 22 or terminal 23 but does connect with the terminal 25. When energy is supplied to the alternator 10A, winding 24 will attract reed 21 causing it to connect with terminal 23 and to move away from terminal 25, causing winding 24 to become deenergized. Upon the deenergization of winding 24, the resilience of reed 21 will cause it to move away from terminal 23 and to connect with terminal 22 as well as with terminal 25. The circuit for winding 24 will then be completed so that reed 21 again will go through the cycle of operation just described. Winding 24, therefore, will be repeatedly energized and deenergized as long as energy is supplied to its control circuit. When reed 21 connects with terminal 22 current is then supplied to the right-hand portion of primary winding 17 of transformer 10N; and when reed 21 connects with terminal 23, current is then supplied in the opposite direction to the left-hand portion of primary winding 17. Alternating current, therefore, will be induced in the secondary winding 18 of transformer 10N.

The alternator A for each of the other sections functions to supply alternating current to the associated transformer N in a manner identical to that described for alternator 10A.

Each battery 16 is directly connected to the line circuit for the control of the relay H for the section next in rear so that when that section is unoccupied, the associated relay H will be energized. Each relay H controls the line circuit for governing the relay D for the section next in rear so that this rear line circuit will be energized whenever the relay H is energized. Each relay D controls the associated alternator A so that whenever the relay D is energized, the line circuit for the control of the relay J for the section next in rear is supplied with alternating current.

The relays H, D, and J, control the associated signal in the following manner: When the relay H is deenergized (see signal 13), both semaphore arms U and L are in the horizontal position to indicate "stop". When the relay H only is energized (see signal 12), a caution circuit for the upper semaphore arm U of that signal is closed over a path which passes from terminal B through front contact 26 of relay 12H and semaphore arm U to terminal C. Signal 12, therefore, is displaying its upper semaphore arm U in the 45° position and its lower semaphore arm L in the horizontal position to indicate "approach next signal prepared to stop". When the relays H and D are both energized but the relay J is deenergized (see signal 11), the caution circuit for the upper semaphore arm U of that signal remains closed over front contact 26 of relay 11H and a proceed circuit for the lower semaphore arm L of that signal is closed over a path which passes from terminal B through front contact 26 of relay 11H, front contact 27 of relay 11D, back point of contact 28 of relay 11J, and lower semaphore arm L to terminal C. Signal 11, therefore, is displaying its upper semaphore arm U in the 45° position and its lower semaphore arm L in the vertical position to indicate "approach next signal at medium speed". When relays H, D, and J are all energized (see signal 10), the caution circuit for upper semaphore arm U remains closed over front contact 26 of

relay 10H and a proceed circuit for the upper semaphore arm U is closed over a path which passes from terminal B through front contact 26 of relay 10H, front contact 27 of relay 10D, and front point of contact 28 of relay 10J to upper semaphore arm U and terminal C. Signal 10, therefore, is displaying its upper semaphore arm U in the vertical position and its lower semaphore arm L in the horizontal position to indicate "proceed at normal speed".

As here shown, a train K is indicated diagrammatically in the section immediately to the right of location Z so that all line circuits are open with the result that the relays 13H, 13D, and 13J are all deenergized.

Under this condition, relays 12D and 12J are deenergized but relays 12H, 11H, and 10H are all energized over easily traced circuits by battery 16 located at signals 13, 12, and 11, respectively, since the sections associated with these relays are all unoccupied.

Since relay 12H is energized, relay 11D is energized over a circuit which passes from terminal B of battery 16 at signal 12, through front contact 29 of relay 12H, secondary winding 18 of transformer 12N, front contact 30 of relay 4TR, front contact 31 of relay 3TR, relay 11D, front contact 32 of relay 3TR, and front contact 33 of relay 4TR to terminal C of battery 16. Since relay 11H is energized, relay 10D is also energized over an easily traced circuit similar to the circuit just traced for relay 11D.

When relay 11D is energized, the operation of alternator 11A is initiated by the closing of front contact 34 of relay 11D so that primary winding 35 of transformer 10M is supplied with alternating current over a path which passes from one terminal of secondary winding 18 of transformer 11N through front contact 36 of relay 2TR, front contact 37 of relay 1TR, primary winding 35 of transformer 10M, condenser 10F, front contact 38 of relay 1TR, front contact 39 of relay 2TR, battery 16, and front contact 29 of relay 11H to the other terminal of secondary winding 18 of transformer 11N. When primary winding 35 of transformer 10M is supplied with alternating current, secondary winding 40 is energized so that relay 10J is energized.

Since both relays 10H and 10D are energized, the line circuits for the control of the signal (not shown) for the section next in rear of location W are all energized so that that signal also will be displaying the normal proceed indication.

When the train K passes out of the section immediately to the right of location Z, relay 12D will become energized so that alternating current will be supplied to the line circuit for the control of relay 11J to cause signal 11 to display the normal proceed indication.

From the foregoing description of the apparatus embodying my invention, it will be apparent that I have provided simple and reliable apparatus for establishing a three-block, four-indication, system of signaling wherein but three line control wires are required and wherein no pole-changing apparatus is necessary.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a section of railway track, 75

5 a home and a distant relay for said section controlled over separate circuits including at least three conductors extending through the section, means controlled by traffic conditions for supplying current of one character to the circuit for said home relay when the section is unoccupied and for also supplying current of said one character to the circuit for the distant relay under certain traffic conditions in advance of said section, another circuit for said section including an auxiliary relay and at least two of said conductors, means responsive to other traffic conditions in advance of said section for supplying current of a different character to said other circuit for selectively controlling said auxiliary relay, and traffic governing means for said section controlled by said three relays.

2. In combination, a section of railway track, a first line circuit for said section including a pair of line conductors, a second line circuit for said section including another line conductor and one conductor of said pair, a third line circuit also including the last mentioned pair of conductors, track circuit means for governing each 25 of said circuits, means for energizing said first circuit with current of one character, means governed by traffic conditions in advance of said section for energizing said second circuit with current of said one character, means governed by other traffic conditions in advance of said section for energizing said third circuit with current of a different character, a first and a second relay governed by said first and second line circuits respectively, another relay governed by said third circuit, and traffic governing means for said section governed by said three relays.

3. In combination, a section of railway track, a home and a distant relay as well as an auxiliary relay for said section, means for energizing said home relay provided said section is unoccupied, means governed by traffic conditions in advance of said section for energizing said distant relay provided said section is unoccupied, means governed by other traffic conditions in advance of said section for energizing said auxiliary relay provided said section is unoccupied, a signal for said section including a first indication unit and a second indication unit, a circuit for said first unit including a front contact of said home relay, another circuit for said first unit including a front contact of said distant relay and a front contact of said auxiliary relay, and a circuit for said second unit including a front contact of said distant relay and a back contact of said auxiliary relay.

4. In combination, a section of railway track, a first relay and a second relay, means governed by traffic conditions in advance of said section for energizing said first relay only or for energizing said second relay simultaneously with the energization of said first relay, a first line circuit for said section energized when said section is unoccupied, a second line circuit for said section energized when said first relay is energized, a third line circuit for said section energized when said second relay is energized, a home and a distant and an auxiliary relay governed by said three line circuits respectively, and a signal for said section governed by said last mentioned relays.

5. In combination, a section of railway track, a first relay and a second relay, means governed by traffic conditions in advance of said section for energizing said first relay only or for energizing said second relay simultaneously with the ener-

gization of said first relay, a first line circuit for said section energized by direct current when said section is unoccupied, a second line circuit for said section energized by direct current when said first relay is energized, a third line circuit for said section energized by alternating current when said second relay is energized, two direct current relays governed by said first and second line circuits respectively, an alternating current relay governed by said third line circuit, and a signal for said section governed by said two direct current relays and by said alternating current relay.

6. In combination, a section of railway track, a first relay and a second relay, means governed by traffic conditions in advance of said section for energizing only said first relay or for energizing said second relay simultaneously with the energization of said first relay, a first line circuit for said section including a pair of line wires, a second line circuit for said section including another line wire and one wire of said pair of wires, a transformer having a primary winding and a secondary winding, a third line circuit for said section including said secondary winding connected in series with the last mentioned pair of line wires, means for energizing said first line circuit with direct current when said section is unoccupied, means for energizing said second line circuit with direct current when said first relay is energized, means for energizing said primary winding with alternating current when said second relay is energized, two direct current relays controlled by said first and second line circuits respectively, an alternating current relay controlled by said third line circuit, and a signal for said section governed by said three last mentioned relays.

7. In combination, a section of railway track, a first relay and a second relay, means governed by traffic conditions in advance of said section for energizing only said first relay or for energizing said second relay simultaneously with the energization of said first relay, a first line circuit for said section including a pair of line wires, a second line circuit for said section including another line wire and one wire of said pair of wires, a transformer having a primary winding and a secondary winding, a third line circuit for said section including said secondary winding connected in series with the last mentioned pair of line wires, means for energizing said first line circuit with direct current when said section is unoccupied, means for energizing said second line circuit with direct current when said first relay is energized, means including an alternator for energizing said primary winding when said second relay is energized, two direct current relays and an alternating current relay governed by said three line circuits respectively, and a signal for said section governed by said last mentioned relays.

8. In combination, a section of railway track, a first relay and a second relay, means governed by traffic conditions in advance of said section for energizing only said first relay or for energizing said second relay simultaneously with the energization of said first relay, a first line circuit for said section including a pair of line wires, a second line circuit for said section including another line wire and one wire of said pair of wires, a transformer having a primary winding and a secondary winding, a third line circuit for said section including said secondary winding connected in series with the last mentioned

pair of line wires, means for energizing said first line circuit with direct current when said section is unoccupied, means for energizing said second line circuit with direct current when said first relay is energized, an alternator connected to said primary winding, means for energizing said alternator when said second relay is energized, two direct current relays and an alternating current relay controlled by said three line circuits respectively, and a signal for said section governed by said last mentioned relays.

9. A railway signal system comprising a stretch of railway track divided into sections, a track circuit including a track relay for each section, a first and a second and a third line circuit for each section each governed by the associated track relay, means for each section for energizing the associated first line circuit, means for each section for energizing the associated second line circuit, provided the section next in advance is unoccupied, means for each section for energizing the associated third line circuit provided the two sections next in advance are both unoccupied, a first and a second and a third line relay for each section governed by the three associated line circuits respectively, and traffic governing means for each section governed by the associated line relays.

10. A railway signal system comprising a stretch of railway track divided into sections, three signal control relays for each section, means for each section effective when such section is unoccupied for energizing only one of the associated relays or for energizing only two of the associated relays or for energizing all three of the associated relays in accordance with traffic conditions in advance of the associated section, and a signal for each section controlled by the associated three relays and arranged to display one proceed indication or another proceed indication or still a different proceed indication according as only one or only two or all three relays respectively are energized.

11. In combination, a plurality of successive block sections of railway track each having a first line circuit including a pair of line conductors and a second line circuit including another line conductor and one conductor of said pair, means governed by traffic conditions in each section for

controlling the circuits through the line conductors for said section, each section having a first direct current relay supplied with current by said first line circuit and a second direct current relay supplied with current by said second line circuit, each section having associated therewith means for supplying direct current to the first line circuit of the adjacent section in the rear, each section having means controlled by the supply of direct current to the first line circuit for supplying direct current to the second line circuit of the adjacent section in the rear, each section having an alternating current generator operated on the supply of direct current to supply alternating current to a circuit including two of the line conductors of the first and second line circuits of the adjacent section in the rear, the supply of direct current to said generator being controlled by one of the direct current relays for the section with which the generator is associated, each section having a third relay responsive only to alternating current supplied to the line conductors for such section, and a signal for each section controlled by said first, second and third relays.

12. In combination, a section of railway track, a first direct current relay and a second direct current relay controlled over separate line circuits including at least three conductors extending through the section, a third line circuit for said section including an alternating current relay and at least two of said conductors, track circuit means governing each of said line circuits, an alternating current generator operated on the supply of direct current to supply alternating current to the third line circuit of the adjacent section in the rear, means controlled by traffic conditions in advance of said section for supplying current of the appropriate character to one of said line circuits, means controlled by said relays for selectively supplying current of the appropriate character to the line circuits of the adjacent section to the rear, means controlled by one of said direct current relays for supplying direct current to said alternating current generator, and traffic governing means for said section controlled by said three relays.

GEORGE R. PFLASTERER.
